CLAIM

The ornamental design for a swimsuit, as shown and described.

DESCRIPTION

FIG. 1 is a front view of a swimsuit on a model showing our new design according to the present invention.

FIG. 2 is a rear view of the swimsuit of FIG. 1.

FIG. 3 is a left-side view of the swimsuit of FIG. 1; and,

FIG. 4 is a right-side view of the swimsuit of FIG. 1.

The broken lines in the figures are provided for environment only and form no part of the claimed design.
